DESIGN FOR A MARINE INDICATOR

Walter G. Huckabee, Silver Grove, Ky.

Application March 22, 1944, Serial No. 112,989

Term of patent 14 years

(Cl. D72—1)

To all whom it may concern:

Be it known that I, Walter G. Huckabee, a citizen of the United States, residing at Silver Grove, in the county of Campbell and State of Kentucky, have invented a new, original, and ornamental Design for Marine Indicators, of which the following is a specification, reference being had to the accompanying drawings, forming part thereof.

Fig. 1 is a top plan view of a marine indicator, showing my new design.

Fig. 2 is a side elevational view of the marine indicator of Fig. 1.

Fig. 3 is a front end elevational view of the marine indicator of Fig. 1.

I claim:

The ornamental design for a marine indicator, as shown.

WALTER G. HUCKABEE.
